Primary Examiner — R. Johnson

(74) *Attorney, Agent, or Firm* — Olive Law Group, PLLC

(57) **CLAIM**

The ornamental design for an electronic drum set, as shown and described.

DESCRIPTION

FIG. 1 is a top, front and right side perspective view of an electronic drum set showing my new design;

FIG. 2 is a bottom, rear, left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion taken at line-9 in FIG. 8.
